UNITED STATES PATENT OFFICE.

JOHN ERICKSON, OF CHICAGO, ILLINOIS, ASSIGNOR TO DENIO GENERAL ELECTRIC COMPANY, OF ROCHESTER, NEW YORK, A CORPORATION OF NEW YORK.

FIRE-ALARM SIGNAL-BOX FOR AUTOMATIC TELEPHONE SYSTEMS.

1,089,404.

Specification of Letters Patent. Patented Mar. 10, 1914.

Application filed December 28, 1911, Serial No. 668,223. Renewed October 4, 1913. Serial No. 793,470.

To all whom it may concern:

Be it known that I, JOHN ERICKSON, of Chicago, in the county of Cook and State of Illinois, have invented certain new and useful Improvements in Fire-Alarm Signal-Boxes for Automatic Telephone Systems; and I do hereby declare the following to be a full, clear, and exact description of the same, reference being had to the accompanying drawings, forming a part of this specification, and to the reference-numerals marked thereon.

My present invention relates to signal boxes for fire alarm systems, and has for its object to provide an apparatus adapted particularly to be used in conjunction with those telephone systems in which the central office connections are set up or established automatically by electromagnetically operated switching devices. The signal box or apparatus embodying my invention is adapted to actuate or automatically control the central office switching mechanism to establish a connection between a subscriber's circuit and fire alarm headquarters, and thereafter to despatch the signal or ring in the number or code signal of the subscriber's station at which the box is located.

My invention also has for its object to provide in conjunction with apparatus of this character, an electromagnetic device which is at all times associated with the subscriber's circuit, having a movable part which will be actuated by the current on the line when the operation of the fire alarm box occurs during the period the subscriber's circuit is being used for telephonic purposes, which will so control the operation of the box that the movement of its parts is arrested temporarily until the central office switches have been restored to their normal positions by the subscribers' act of "hanging up" their receivers.

To these and other ends the invention consists in certain improvements and combinations of parts, all as will be hereinafter more fully described, the novel features being pointed out in the claims at the end of the specification.

In the drawings: Figure 1 is a front elevation of the mechanism of a signal box showing the operating parts constructed in accordance with my present invention and in their normal position, the casing of the box being removed; Fig. 2 is a side elevation;

Fig. 3 is a detail view of the gear train and the stop devices; Fig. 4 is a detail view showing the several contact controlling members and the coöperating elements arranged to actuate them periodically; Fig. 5 is a detail view of the releasing push button or member, and Fig. 6 is a detail diagrammatic view showing the arrangement of the signal box in conjunction with an automatic telephone system.

Similar reference numerals in the several figures indicate the same parts.

Fire alarm signals or call boxes embodying my present invention are employed in conjunction with a subscriber's circuit of a telephone system for despatching automatically a call or signal to fire alarm headquarters. In those telephone systems in which the central office connections are set up or established manually, a subscriber's circuit is connected to the fire alarm circuit by the central office operator, and a signal is transmitted from the circuit thus established. In the automatic telephone systems, where the central office connections are established by the use of electro-mechanically operated switching mechanism, the signal box must be provided with means for transmitting the necessary impulses for effecting the switching operation to connect the subscriber's circuit on which the signal box is located with the fire alarm circuit, and after this circuit has been thus established, the impulses of current for sounding the alarm or recording the number of the signal box, are transmitted.

In automatic telephone systems the normal condition of the switches is restored in readiness for subsequent operations only when one or both of the connected subscribers hang up or replace their receivers, and thereby grounding and then opening the line at the switch hook contacts of their respective instruments. For the successful operation of a fire alarm signal box it is, therefore, necessary when two subscribers' lines are connected, that the first operation of the box shall produce such an effect on the line that the subscribers will, of necessity, hang up their receivers, and that the box will thereafter take possession of the subscriber's line on which it is arranged, so that, if the subscriber, who was previously connected, or any other subscriber, endeavors to make connection therewith, a condition

equivalent to the so called "busy condition" will exist.

In illustrating my present invention, I have shown the mechanism mounted upon a base plate 1 comprising the clock train shown in Figs. 2 and 3, driven by the spring 2, imparting continuous rotary movement to the arbor 3. The gear train also embodies speed controlling mechanism in the form of 5 a rotating notched wheel 4, with which operates the escapement 5, the oscillation of which is governed by a fan 6 connected thereto. Also mounted on the base 1 beneath the parts just described, is a restraining device which may be released manually. In its present form the restraining device 10 comprises a member 7 guided in a sleeve 8 on a frame piece 9, which is held in its projected position against the tension of spring 15 10 by an underlying finger 11 on the frame 9, which is adapted to be moved from beneath the plunger by the operation of the short lever arm 12, on the face of which appears the word "Push", which is visible through 20 a sight aperture 13 in the cover 14, which encloses the mechanism, and is removably attached to the base 1.

The device which restrains the operation of the clock train is preferably arranged beneath one end of the fan 6 in such position that when released and retracted by the springs 10 will be moved out of the path of the fan. At the opposite end of the latter is a finger or reed 15 attached to the armature 30 16 of a pair of polarized electromagnets X and Y. The latter are supported in a suitable frame attached to the base 1, which also carries the pivot points of the armature 16 upon which is mounted a permanent magnet 17. The relation of the coil windings and the poles of the permanent magnet 17 are such that the armature 16 is normally inclined in the direction shown in Figs. 1 and 2, in which position the reed or finger 40 15 is held out of engagement with the fan 6, this position being further assured, when the coils of the magnets are not energized, by a delicate spring 18.

The operating mechanism of the signal box further comprises various contacts, as shown in Figs. 1 and 6, and cooperating devices for actuating them, said devices comprising a switch operating wheel 19 and an alarm signal wheel 20, both mounted on the 50 arbor 3, and a pivoted lever 21 controlled by the switch operating wheel 19. The arbor 3 also carries an arm, supporting at diametrically opposite points, fingers 22, 22^a, which, during the rotation of the arbor, perform a dual function upon each half revolution thereof, first disengaging a trip lever 23 from the spur gear wheel 24, then rotating the latter a single step. The trip, it will be noticed, is provided with a downwardly 55 60 65 extending finger 25, the extremity of which

lies in the path of the projections 22, 22^a, as do also the teeth of the spur gear 24. The latter is mounted upon a stud shaft and is connected to a cam member having two different sets of projections and serving to 70 rock the lever arms 26 and 27, which are supported upon a common pivot 28, these levers controlling the opening and closing of various sets of contacts to effect the necessary switching operations at the central office or 75 exchange in conjunction with the movement of the lever 21. The lever 26 controls two sets of contacts a, b, and c, d, which are normally closed and held closed by the insulating members 26^a and 26^c engaging the 80 springs a and c respectively. The lever 27 controls the movement of the spring e permitting it to ply between the springs f and g. Associated with the contacts e and d is the third contact h.

The cam surfaces of the cam member, before referred to, which is moved intermittently by the spur gear wheel 24, are arranged to produce coördinate operations between the various sets of contacts by effecting relative movements of the arms 26 and 27, as will be seen from an inspection of Figs. 4 and 6.

The lever 21 carries at its upper end an insulating stud 21¹ which engages the spring i, and according to the direction of movement of the lever permits it to engage either the spring j or the spring k parallel with which is a fourth contact spring l.

The spring contacts of the box are arranged in the subscriber's circuit of an automatic telephone exchange system, as shown in Fig. 6, and their movement is so controlled that at proper times they will by their conjoint action effect the necessary 100 operation and control the central office switching apparatus. In order to illustrate this feature of the apparatus, there has been shown in Fig. 6 well known types of switches, with which those conversant with 105 the art of automatic telephony are familiar. In the arrangement of such switches at the central office, they are divided into groups or sets known generally as line switches, and first and second selectors and connectors, according to the number of lines in the exchange to be served, but as the operation of a plurality of switches in setting up a connection is generally the same as the operation of a single switch, inasmuch as they 110 operate successively, there are merely shown for convenience of illustration, two subscribers' instrument circuits, the line switch contacts of each and a single selector and connector. The two subscribers' circuits are 115 indicated by R and V and R' and V', these characters also indicating the vertical and rotary sides of the respective lines.

Automatic switches of the character shown diagrammatically are disclosed in detail in 120 125 130

U. S. Letters Patent, Nos. 815,176 and 815,321, granted March 13, 1906, to Keith and Erickson, and in the diagrammatic illustration the selector switch S is shown as comprising a vertical and rotary movable shaft 30 carrying wipers or brushes s, s' , which will be understood to co-operate with the sets of contacts arranged in circular rows and vertical tiers, the shaft being movable vertically step by step to align the brushes with the different rows of contacts by means of ratchet mechanism actuated by what is known as the vertical magnet, indicated by V^2 . Similarly the shaft is revolved by a pawl and ratchet actuated by impulses of current transmitted through a rotary magnet R^2 , the respective circuits of said magnets being controlled by a contact arm w of the side switch mechanism actuated by the so-called private magnet P . The switch arm w normally engages the contact x while current impulses are transmitted to the vertical magnet, and when these cease the confirming impulse transmitted from the rotary side of the line actuates the side switch mechanism to step the switch arm into engagement with the contact y , cutting in the rotary magnet and breaking the circuit of the vertical magnet.

The side switch magnet is illustrated diagrammatically, comprising an armature p of the magnet P and carrying an arm and a spring finger having offset ratchet teeth, which control the stepping along of the projection p' attached to the spring impelled switch arm w to control its stepping movement.

In the diagrammatic illustration in Fig. 6, the vertical and rotary sides of the subscriber's telephone line are shown as leading from the wipers s, s' through the line switch contacts to the subscriber's telephone instrument A and the calling device B therefor. The calling device, when employed for operating the switch mechanism may, as before, be the well known apparatus, and for these reasons details essential to the operation of the telephone system *per se* may be omitted. For this reason only those parts of the central office switches have been shown which serve to illustrate the operation of the fire alarm signal box constructed in accordance with my invention and the objects attained thereby. It will, therefore, be understood that many features and details of the switching mechanism have been omitted, as well as other things which it is necessary to take into consideration in connection with the practical operation of an automatic telephone system, since these are well known in the art.

A source of current for operating the selector switch mechanism is supplied by the battery X^{10} grounded at one side, as indicated by w^{10} , one pole being connected by the wire w' to the switch arm w and other pole

to the wire p^2 leading to the armatures v and r respectively, arranged in front of the vertical relay S' and adapted to be attracted, when the latter is energized, into engagement with the contacts of the wires v^2, r^2 , leading respectively to the vertical and rotary magnet V^2, R^2 , which latter are also connected to the contacts x, y , of the side switch. The battery lead p^2 is connected by the wire p^3 to the private magnet, the circuit of which is completed by the wire p^4 leading to the rotary line wire R . The relay S' is connected by the wires s^2 and s^3 to one side of the battery and to the vertical line wire V .

The connector switch mechanism indicated generally by T comprises the vertically movable and horizontally revoluble wiper shaft 40 carrying the brushes t, t' , which are connected with the multiple contacts or trunk terminals of the connector switch S by the wires V^3 and R^3 , in which are interposed the condensers C . The mechanism for operating the wipers t, t' of the connector switch operates to raise the wiper shaft and subsequently rotate it after the selector switch has completed its operation and cut the line through to the connector switch. The latter comprises the vertical magnet V^4 , the rotary magnet R^4 , the vertical relay T' , and the private magnet P^4 . The battery X^{100} supplies current for the circuits of the several magnets just mentioned. In practice, the side switch mechanism before referred to, comprises a plurality of switch arms, preferably four in number, each of which performs a different function, but as these are well known I have only shown in Fig. 6 two side switch arms w^2 and t^2 on the connector switch, the former for cutting in successively the vertical and rotary magnets, and the latter for supplying ground or completing the battery connection when the connector switch wipers t, t' have stopped their movement and connected with the proper outgoing line or "called" subscriber's circuit.

It is deemed a desirable feature in automatic telephone practice to provide means for supplying battery current to the line for talking purposes when the called subscriber "answers in" by the act of removing his receiver and closing the switch contacts, and it will be understood that this act "cuts back" current for talking purposes to the calling subscriber's end of the line. In accomplishing these objects there is associated with the connector switch a double wound relay N, O , provided with an armature m , which, when attracted, moves the contact spring m' out of engagement with the contact m^2 into engagement with a contact m^3 . One end of the coil N is connected by the wire n to the wire V^5 connected to the brush t' ; likewise one end of the coil O is connected by the wire o to the wire R^5 lead-

ing to the brush t , said connections being on the called party's side of the condensers C. The other extremity of the coil of the magnet N is connected by the wire n^1 to one side of the battery X^{100} , and through the wire n^2 it is also connected to the conductor V³ of the calling party's circuit. A tap leads from this wire n^2 , as indicated by n^3 , to spring m^2 . The latter is normally in engagement with the spring m' , which is connected by the wire m^4 to rotary line wire R². The circuit of the relay O is completed through the switch arm t^2 when the latter is in its third position of engagement with the contact grounded by the wire t^3 , the switch arm being connected by the wire t^4 with one end of the coil of relay O, and also joined to the spring m^2 .

It will be understood from the foregoing description in connection with Fig. 6 that the calling subscriber gets no current for talking purposes until the called subscriber responds. When the connection is first made with the called subscriber's line the live side of the battery X^{100} is connected through coil N with the called end of the line, the circuit being completed to ground through the coil O and side switch arm t^2 when the called party "answers in." The energizing of the coils N and O closes the contacts m^1 , m^3 connecting the battery X^{100} across the calling end of the line.

In illustrating the switches, the means for releasing them has not been disclosed, but it will be understood however, that as soon as the calling subscriber hangs up his receiver both sides of the line circuit are grounded at the subscriber's station, which through agencies not shown, releases the connector switch shaft permitting it to rotate and descend to its normal position. The connector switch in doing this subsequently causes each of the selector switches to be restored to their normal positions as well as the line switch.

Before proceeding with a detail description of the operation of the fire alarm signal box, the detail connection of the various contacts will be described.

The subscriber's line or circuit wires V, R lead respectively to the contact springs c , a , which are normally closed in engagement with the springs d , b , the former leading to the instrument set over the wire d' and the latter over the wire b' . At the subscriber's station the calling device B is connected to ground by conductor B' and by conductor B² with the contact spring e . The four contact springs i , j , k and l are arranged in circuit as follows: Spring i is tied to spring f by wire i^2 . Spring j is connected to vertical line wire V by wire j^2 . Spring k is connected by the wire k' with rotary line wire R. Vertical line wire V is also connected with spring g by the wire g' . The polarized

coils X, Y, are arranged in a branch circuit adapted at certain times to be bridged across the subscriber's instrument circuit, and for this reason one end of the coil Y is connected by the wire Y' to spring l , and the other extremity of the coil X is connected by the wire Y² with the spring h .

The cam member operated by the spur gear wheel 24 controlling the levers 26 and 27 is provided with a series of surfaces controlling each of said levers to produce different combinations of circuits several different times during each complete rotation of arbor 3, as will be seen from inspection of the diagrammatic view in Fig. 6, which shows the parts in the normal position. The first movement of the spur gear wheel 24 breaks the contacts of spring $a-b$, $c-d$. The signal box mechanism continues to run until the first projection on the wheel or member 19 moves the lever 21 and closes together springs i , k , l . The act of opening the sets of contacts $c-d$, $a-b$, cuts off the subscriber's telephone circuit on which this mechanism is installed, and the closing of the contacts i , k and l grounds and short circuits said subscriber's line through the polarized relay coils X, Y, the springs e , f and c , h being closed at this moment. This grounding of both sides of the line is sufficient to effect the restoring of the central office switches, should it happen that the subscriber on this line was the calling party, who, in order to converse with another subscriber, initiated the call. The next step in the operation is the opening of the contacts $e-f$ to remove the ground connection of the line above mentioned. The polarized relay coils X, Y then remain bridged across the line through contacts $k-l$ and $h-c$.

The third step is the breaking of the contacts of the springs $h-c$ to clear the line.

The fourth step consists in making contact between springs $e-f$ to ground the spring i after which the impulses over the vertical and rotary sides of the line may be transmitted to automatically effect the operation of the central office switches. In this connection it will be noted that the wheel or member 19 is provided with indentations which permit movement of the lever 21 so that spring i engages contact j to provide the necessary vertical impulses and that said wheel has projections which cause the lever to move the spring i into contact with h , whereby the necessary confirming impulse, or impulses, are despatched over the rotary side of the line. In practice it is customary to provide the circuit leading to fire headquarters with terminals on the first selector switch, and in Fig. 6 it is shown comprising the line wires E, F leading to the magnet G, controlling an armature in a local circuit of a magnet G' by means of which a punch or other recording device H may be operated to

record the signal. After the circuit E and F has been connected by the wipers s, s' the group of alarm indicating impulses are despatched by the successive opening and closing of the contact springs g—e, the former of which is moved laterally when the block of insulating material g² coöperating with the wheel 20 is permitted to drop into the indentations in the face of the wheel. The 10 operation of the springs g and e, just described, is known as the fifth step in the operation of the box mechanism, and at the time the movement of the spring g occurs the springs e and f are disconnected and spring 15 e is in engagement with spring g.

The sixth step consists in closing the contacts h—c and e—f, also contacts i, k and l. The circuits thus established prepare the selector switches at the central office for their 20 release.

The seventh step is the breaking of all contacts to open all the circuit connections allowing the full release of the selector switches.

25 The eighth movement of the cam members causes contact to be made between springs a—b and c—d to restore the subscriber's telephone service.

In the event it is desired to despatch an 30 alarm signal the push lever or member 12 is operated to release the plunger 7, which is then retracted by the spring 10, and the escapement 6 then being free to vibrate permits the driving devices of the signal box to 35 begin their operation. A partial revolution of the arbor 3 causes the projection 22 to lift the trip 23 and impart one step to the gear wheel 24. The first operation of the cam member then cuts off the telephone sub-

40 scribe's instrument, and short circuits and grounds the line through the polarized relay coils X, Y. If the subscriber on whose line the box is installed is using his telephone circuit and has been the calling subscriber, who initiated the previous call and 45 set up the connection, the mechanism of the box is able to release the existing switch connections, and no pause or delay occurs in the operation of the signaling mechanism.

50 However, should a telephone connection have been previously established from some other telephone to the circuit, upon which the signal box is installed, the operation of the box will not release the circuit, and it is 55 necessary, therefore, to arrest the movement of the signaling mechanism, until the switches have been restored to their normal condition, and to provide means so that when this restoration of the lines has occurred the box will automatically be released and permitted to perform its functions in the usual manner. To this end the electromagnets X and Y are brought into the circuit.

65 In practice when a fire alarm mechanism

is installed upon a subscriber's line a reversal is made in the wires between the connector terminal contacts and the line switch normal contacts, so that when a call originates on the box subscriber's telephone circuit, and the connection is established, there is negative battery on the vertical side of the line and positive battery on the rotary side of the telephone line, consequently in every connection made to this line the battery 70 when supplied, for talking purposes is connected through the connector switch at its negative side to the rotary wire and at its positive side to the vertical wire. Therefore, when the signal box mechanism is operated after the subscriber has been called by some other party, the flow of battery current through the coils X, Y is in such a direction as to attract the armature 16, so as to move the finger or reed 15 into engagement with the fan 6. Now when this condition exists the called subscriber has been cut off and the calling subscriber, finding that his connection has been disturbed hangs up his receiver and by so doing restores his own 80 selector switches, upon the release of which the current supplied through the connector switch to the telephone line is removed; thereupon the polarized armature 16 assumes its normal position, the driving mechanism of the signal box continues to run on, and during this movement actuates the central office switches to pick up the fire headquarters circuit and record the alarm signal. The latter is preferably despatched 90 several times in succession and after the last "round" of the box the subscriber's telephone circuit is restored to its normal condition.

I claim as my invention:

1. In a signal mechanism for use on a subscriber's circuit of an automatic telephone system comprising central office switching mechanism for connecting two subscribers' circuits, the combination with a mechanism for transmitting current impulses to effect the operation of the switching mechanism embodying driving devices, of means for restraining the operation of the driving devices comprising a polarized 110 armature adapted to be influenced and moved into arresting position by the current supplied to the line when two subscribers' circuits are connected for conversational purposes.

2. In a fire alarm signal mechanism, for subscribers' circuits of an automatic telephone exchange comprising automatic central office switching mechanism and circuit arrangements for cutting back battery current for talking purposes when the called party answers, the combination with mechanism for controlling the switches to set up a connection between two circuits, devices for driving said mechanism and means 125 for

- which is normally inoperative for restraining its operation, comprising an armature, and electro-magnet adapted to be bridged across the subscriber's circuit when the signal mechanism has been started and to be energized when said circuit has been connected to another subscriber's circuit, and means for opening the first mentioned subscriber's circuit after said magnet has been energized.
3. A signal apparatus adapted to be used on a subscriber's circuit of an automatic telephone exchange, comprising a driving mechanism, means operated thereby for transmitting current impulses to actuate the central office switches to connect two subscribers' circuits, and subsequently despatch alarm recording impulses, means for arresting said driving mechanism comprising polarized electro-magnetic devices adapted to be actuated into arresting position by the current in the line when two subscribers' circuits are connected and to be actuated into release position when said circuits are disconnected.
4. An alarm system apparatus for use on subscribers' circuits of automatic telephone systems, comprising means for despatching impulses for operating the central office switches and other impulses for recording an alarm, and devices normally set for driving said means, a polarized electro-magnet adapted to be bridged across the line when the driving devices are operated, an armature which is moved in a direction to control the driving devices when said magnet is energized by current of one polarity.
5. In an alarm signal apparatus for use on subscribers' circuits of automatic telephone systems, the combination with means for transmitting current impulses to effect the operation of the central office switches and despatch a signal over a line subsequently connected by the switches and devices for driving said means, of sets of contacts and members operated by the driving devices controlling them for opening the subscriber's instrument circuit and closing a branch circuit bridged thereto having an electro-magnet therein, a polarized armature on said magnet and a member operated thereby for restraining the driving devices normally held in an inoperative position and moved into an operative position by the flow of current employed for talking purposes when a called subscriber has answered.
6. In a signal box mechanism the combination with driving devices having an escapement, impulse despatching members moved thereby and sets of circuit contacts operated by said members, of a plurality of other sets of contacts, members for moving them, a plurality of revoluble cams controlling said members and means intermittently operated by said driving devices for rotating the cams relatively to the movement of the impulse despatching members.
7. In a signal box mechanism the combination with driving devices having an escapement, impulse despatching members moved thereby and sets of circuit contacts operated by said members, of a plurality of other sets of contacts, members for moving them, a plurality of revoluble cams controlling said members, a driving member for rotating the cams and a locking device for said member, an operating device moving with the impulse despatching members and intermittently releasing the locking device and rotating the driving member a partial revolution.
8. In a signal box mechanism the combination with driving devices having an escapement, impulse despatching members moved thereby and sets of circuit contacts operated by said members, of a plurality of other sets of contacts, members for moving them, and means controlling their movement relatively to the movement of the impulse despatching members, polarized electro-magnets having a circuit controlled by one of said sets of contacts, an armature for said magnets and a member controlled thereby and coöperating with the driving devices to either restrain or permit their operation.
9. The combination with an automatic telephone exchange system in which the connection between two subscribers' circuits is set up by automatic switching mechanism and current for talking purposes is cut back when the called subscriber answers, and the switches are restored to normal when the calling party "hangs up", of a signal mechanism comprising means for despatching current impulses to operate the switches and transmit impulses for recording a signal and devices for driving said means, a polarized electro-magnetic mechanism for arresting said driving devices comprising a branch circuit adapted to be bridged across the subscriber's line after the driving devices have commenced their operation, and also adapted to be actuated by the talking current to arrest said devices and contacts in the subscriber's line adapted to be opened to disconnect said line upon commencement of the movement of the driving devices.
